(57) **CLAIM**

The ornamental design for a size indicator for a hanger, as shown and described.

DESCRIPTION

FIG. 1 is a top perspective view of a size indicator for a hanger showing my new design;

FIG. 2 is a bottom elevational view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a side perspective view thereof.

The broken lines shown in the drawings are directed to environment, and are for informational purposes only and form no part of the claimed design.
